UNITED STATES PATENT OFFICE

114,417

DESIGN FOR A LOW WING CANTILEVER MONOPLANE

James G. Taylor, Dayton, Roscoe C. Wilson,
Fairfield, and Oscar A. Swanson, Dayton, Ohio,
assignors to Government of United States of
America, as represented by Secretary of War,
and his successors in office

Application July 22, 1935, Serial No. 57,770

Term of patent 7 years

To all whom it may concern:

Be it known that we, James G. Taylor, Roscoe C. Wilson, and Oscar A. Swanson, citizens of the United States, residing at Dayton, Fairfield, and Dayton, respectively, in the counties of Montgomery, Greene, and Montgomery, respectively, and State of Ohio, have invented a new, original, and ornamental Design for a Low Wing Cantilever Monoplane, of which the following is a specification, reference being had to the accompanying drawing, forming part thereof, wherein:

Fig. 1 is a top plan view of an airplane showing our new design;

Fig. 2 is a front elevational view of the said

airplane design with the landing gear in the retracted position; and

Fig. 3 is a side elevational view of said airplane design with the landing gear lowered in landing attitude.

We claim:

The ornamental design for a low wing cantilever monoplane, as shown and described.

JAMES G. TAYLOR.
ROSCOE C. WILSON.
OSCAR A. SWANSON.
